Charles B. Shepherd, INVENTOR
By W. M. C. Cutshaw, ATTORNEY

UNITED STATES PATENT OFFICE.

CHARLES B. SHEPHERD, OF NEW YORK, N. Y., ASSIGNOR TO WILLARD REID, OF SCARSDALE, NEW YORK.

RAIL ANCHOR.

Application filed April 23, 1928. Serial No. 272,073.

This invention relates to those devices designed to prevent the longitudinal creeping of rails known as rail anchors.

This invention has for an object a rail anchor which is efficient in use and easy to apply and remove, if desired.

Another object of this invention is to provide a rail anchor, the normal length of which is less than the width of the rail base flange which it is intended to engage whereby in its applied position a pressure is exerted transversely to the rail base flange.

A further object of this invention is to provide a rail anchor having a jaw member which includes a yielding and resilient S-shaped, three fold or three ply member adapted to engage the lower surface of the rail base flange.

An additional object of this invention is to provide a rail anchor having a vertical edge-engaging means so constructed that it will give or yield slightly whereby the anchor may be elongated.

Further objects will appear from the following description, hereinafter appended claims and the accompanying drawings in which:

Figure 1 is an isometric view of the anchor forming this invention.

Figure 2 shows the anchor applied in position to a rail base flange, the rail being shown in section.

Figure 3 illustrates one of the positions assumed by the anchor when being applied.

Figure 4 illustrates the relation of parts before and after the anchor has been applied to a rail base flange, the dotted lines showing the position of the various parts of the anchor when applied in position on a rail base flange.

Figure 5 illustrates a modification of the anchor illustrated in Figures 1 to 4 inclusive.

Referring to the drawings and especially to Figures 1 to 4 inclusive in which one modification of my invention is illustrated, the reference numeral 1 designates a body member of the rail anchor. Disposed on opposite ends of the body member 1 are rail flange-engaging means 2 and 2'. The rail flange-engaging means 2 includes a vertical member 3, the inner surface 3' being designed and adapted to engage a vertical edge of the rail base flange. The upper end of the vertical member 3 terminates in a substantially rigid member 4 adapted to engage the upper sur-

face of the rail base flange. This member is preferably made so that it will conform to the shape of the upper surface of the rail base flange. The other end of the vertical member 3 is bent inwardly to form a tie-abutting means 4'. The tie-abutting means 4' is integrally connected to an S-shaped, three fold or three ply member 5 which forms a resilient and yielding member adapted to engage the lower surface of the rail base flange. This yielding member 5 is disposed beneath the substantially rigid member 4 and integrally connected to the body member 1. The upper surface 6 of this member 5 is disposed in a plane normally higher than the plane of the upper surface of the body member 1 and is spaced from said substantially rigid member 4 a distance less than the cross-section of a standard rail base flange. If desired, the end of the S-shaped member may be made to contact with the middle portion of the S-shaped member, as at 7.

Disposed on the opposite end of the body member 1, as previously pointed out, is the flange-engaging means 2'. This flange-engaging means 2' comprises an upturned end or lip 8 designed to engage the vertical edge of the rail base flange. A portion 9 of the body member 1 adjacent this lip member 8 is also made to be in a plane higher than the plane of the body member 1. If desired, this portion 9 may be in the same plane or in a plane higher than that occupied by the upper surface 6 of the yielding member 5. Normally, the anchor is formed so that the distance between the two vertical edge-engaging means 3' and 8 is less than the width of the rail base flange. When applied in position on the rail base flange, due to this construction, a pressure is exerted transversely to the rail base flange.

In applying the rail anchor to the rail base, the member 2 is slipped over the rail base flange and pushed on as far as it will go. At the end of this operation the rail anchor will assume the position illustrated in Figure 3. The anchor is then struck by means of a spike maul or sledge on the outer surface of the vertical member 3 whereby the anchor is distorted and the rigid member 4 pushed or forced on the upper surface of the rail base flange. This is continued until the lip 8 clears the opposite edge of the rail base flange and snaps into position. During the course of the application of the rail anchor to the rail

base flange, due to the various pressures exerted and the fulcrum at 7, the resilient member 5 is depressed and moved inwardly and the body member 1 elongated. Also the vertical member 3 yields outward slightly, the bend at its lower end functioning as a fulcrum.

When applied the anchor will assume the position shown in the dotted lines of Figure 10 4. In position on the rail base flange, the anchor exerts a pressure transversely to the rail base flange at 3' and 8. It also exerts an upward pressure at 6 and 9. A downward pressure is exerted by the substantially rigid member 4. It is thus seen that this anchor has five points of pressure contact whereby a powerful holding grip is attained.

In Figure 5, I have illustrated a modification of the anchor described above and illustrated in Figures 1 to 4. In this modification one portion 10 of the S-shaped member is adapted to engage the vertical member 3 in the vicinity of the bend 11. This serves as a fulcrum in the operation and application of 25 the anchor and renders the anchor somewhat more resilient during its application.

Since it is obvious that various modifications may be made in the specific details above-described without departing from the 30 nature of this invention, I do not intend to limit myself thereto except as defined in the claims.

I claim:

1. A rail anchor comprising a body member, rail base flange-engaging means disposed on opposite ends thereof, one of said rail base flange-engaging means having a yielding and resilient member adapted to engage the lower surface of a rail base flange and 35 normally in a plane higher than said body member and means adapted to engage a vertical edge of said flange, said means adapted to yield and give whereby the length of the anchor is increased.
2. A rail anchor including rail base flange-engaging means which comprises means adapted to engage the upper surface of a rail base flange, a yielding S-shaped, three fold or three ply member disposed beneath 40 said first mentioned means and adapted to engage the lower surface of said rail base flange and means connecting both of said means and adapted to engage the vertical edge of said rail base flange.
3. A rail anchor comprising a body member, rail base flange-engaging means disposed 45 on one end thereof, said rail base flange-engaging means comprising means adapted to engage the vertical edge of a rail base flange, means adapted to engage the upper surface 50 of said rail base flange and a yielding S-shaped member adapted to engage the lower surface of said rail base flange and rail base flange-engaging means disposed on the other 55 end of said body member.

4. A rail anchor comprising a body member, rail base flange-engaging means disposed on one end thereof, said rail base flange-engaging means comprising yielding means adapted to engage the vertical edge of a rail base flange, means adapted to engage the upper surface of said rail base flange and a yielding S-shaped member adapted to engage the lower surface of said rail base flange and rail base flange-engaging means disposed on 70 the other end of said body member.

5. A rail anchor comprising a body member, rail base flange-engaging means disposed on one end thereof, said rail base flange-engaging means comprising means adapted to engage the vertical edge of a rail base flange, means adapted to engage the upper surface of said rail base flange and a yielding S-shaped member adapted to engage the lower surface of said rail base flange and rail base flange-engaging means disposed on the other end of said body member, the upper surface of 80 said S-shaped member and the surface adjacent the last named rail base flange-engaging means being disposed in a plane higher than 85 said body member.

6. A rail anchor comprising a body member, rail base flange-engaging means disposed on one end thereof, said rail base flange-engaging means comprising substantially rigid means to engage the upper surface of a rail base flange, a yielding S-shaped member disposed beneath said substantially rigid means and adapted to engage the lower surface of 90 said rail base flange yielding means adapted to engage the vertical edge of said rail base flange connecting said upper and lower rail base flange-engaging means, and rail base flange-engaging means disposed on the opposite side of said body member.

7. A rail anchor comprising a body member, rail base flange-engaging means disposed on one end thereof, said rail base flange-engaging means comprising substantially rigid means to engage the upper surface of a rail base flange, a yielding S-shaped member disposed beneath said substantially rigid means and adapted to engage the lower surface of 110 said rail base flange, said S-shaped member having one of its ends contacting its middle 115 portion, yielding means adapted to engage the vertical edge of said rail base flange connecting said upper and lower rail base flange-engaging means, and rail base flange-engaging means disposed on the opposite end of 120 said body member.

8. A rail anchor comprising a body member, rail base flange-engaging means disposed on one end thereof, said rail base flange-engaging means comprising substantially rigid 125 means to engage the upper surface of a rail base flange, a yielding S-shaped member disposed beneath said substantially rigid means and adapted to engage the lower surface of said rail base flange, yielding means adapted 130

to engage the vertical edge of said rail base flange connecting said upper and lower rail base flange-engaging means, said S-shaped member having a portion thereof contacting 5 with said vertical edge-engaging means, and rail flange-engaging means disposed on the opposite end of said body member.

9. A rail anchor comprising a body member, rail base flange-engaging means disposed 10 on one end thereof, said rail base flange-engaging means comprising substantially rigid means to engage the upper surface of a rail base flange, a yielding S-shaped member disposed beneath said substantially rigid means 15 and adapted to engage the lower surface of said rail base flange, said S-shaped member having one of its ends contacting its middle portion, yielding means adapted to engage the vertical edge of said rail base flange connecting 20 said upper and lower rail base flange-engaging means, and rail base flange-engaging means disposed on the opposite end of said body member, the upper surface of said S-shaped member and the surface adjacent said 25 last named rail base flange-engaging means disposed in a plane higher than said body member.

10. A rail anchor comprising a body member, rail base flange-engaging means disposed 30 on one end thereof, said rail base flange-engaging means comprising substantially rigid means to engage the upper surface of a rail base flange, a yielding S-shaped member disposed beneath said substantially rigid means 35 and adapted to engage the lower surface of said rail base flange, yielding means adapted to engage the vertical edge of said rail base flange connecting said upper and lower rail base flange-engaging means, said S-shaped 40 member having a portion thereof contacting with said vertical edge-engaging means, and rail base flange-engaging means disposed on the opposite end of said body member, the upper surface of said S-shaped member and the surface adjacent said last named rail base 45 flange-engaging means disposed in a plane higher than said body member.

11. A rail anchor normally of a length less than the width of a standard rail base flange 50 comprising a body member, rail base flange-engaging means disposed on one end thereof,

said rail base flange-engaging means comprising substantially rigid means to engage the upper surface of a rail base flange, a yielding S-shaped member disposed beneath 55 said substantially rigid means and adapted to engage the lower surface of said rail base flange, said S-shaped member having one of its ends contacting its middle portion, yielding means adapted to engage the vertical edge 60 of said rail base flange connecting said upper and lower rail base flange-engaging means, and rail base flange-engaging means disposed on the opposite end of said body member.

12. A rail anchor normally of a length less than the width of a standard rail base flange comprising a body member, rail base flange-engaging means disposed on one end thereof, said rail base flange-engaging means comprising substantially rigid means to engage the upper 65 surface of a rail base flange, a yielding S-shaped member disposed beneath said substantially rigid means and adapted to engage the lower surface of said rail base flange, said S-shaped member having one of its ends contacting its middle portion, yielding means adapted to engage the vertical edge of said rail base flange connecting said upper and lower rail base flange-engaging means, and rail base flange-engaging means disposed on 70 the opposite end of said body member, the upper surface of said S-shaped member and the surface adjacent said last named rail base flange-engaging means disposed in a plane higher than said body member. 75

13. A rail anchor comprising a body member, rail base flange-engaging means disposed on one end thereof, said rail base flange-engaging means comprising substantially rigid means to engage the upper surface of a rail 80 base flange, a yielding member disposed beneath said substantially rigid means and adapted to engage the lower surface of said rail base flange, a yielding vertical member adapted to engage the vertical edge of said 85 rail base flange and connecting said upper and lower rail base flange-engaging means, said lower engaging means contacting with said vertical member.

In testimony whereof, I have affixed my signature to this specification.

CHARLES B. SHEPHERD.
